DRUM LIFTING ATTACHMENT FOR CRANE TRUCKS

Edwin J. Roy, Baton Rouge, La.

Application July 24, 1946, Serial No. 685,986

5 Claims. (Cl. 212—9)

1

My present invention relates generally to improvements in automotive or industrial trucks of the vertically swinging crane type having a hoist-line and horizontally pivoted carrier, and more specifically to a manually controlled and power operated lifting mechanism for crane trucks in the nature of a unitary assembly or equipment for attachment to and use with the truck in lifting and transporting certain types of loads.

While the lifting mechanism of my invention is well adapted for use in various ways, it is especially designed for facile handling of cylindrical drums, or other liquid containers, in such manner as to eliminate the possibility of spillage or waste of the contained liquid.

The primary object of the invention is to equip a crane truck of conventional type with a lifting or pick-up mechanism that is simple in construction and convenient in operation and control for effective and efficient use lifting, carrying or transporting, and depositing, a load or container of this nature.

The invention consists in certain novel combinations and arrangements of parts as will hereinafter be more fully set forth. In the accompanying drawings I have illustrated one complete example of the physical embodiment of my invention wherein the parts are combined and arranged according to one mode I have so far devised for the practical application of the principles of my invention, but it will be understood that various changes and alterations may be made in these exemplifying drawings and mechanical structures, within the scope of my appended claims, without departing from the principles of the invention.

Figure 1 is a top plan view of a conventional automotive crane truck of the industrial type with which my invention is embodied, with the mechanism shown in released position with relation to a cylindrical drum or other load-container.

Figure 2 is a view in side elevation of the crane truck in Fig. 1.

Figure 3 is a top plan view of the truck with parts in horizontal section, showing the lifting mechanism and carrier attached to the drum.

Figure 4 is a view in side elevation showing the carrier and drum in uplifted position for transportation; and

Figure 5 is an enlarged detailed sectional view approximately on the line 5—5 of Figure 1.

In order that the general arrangement and relation of parts may readily be understood I have illustrated a conventional truck of this type

2

having upwardly converging uprights 1, 1 and an inclined crane 2 forming the main frame which is rigidly united with the usual chassis 3 of the automotive truck.

5 The hoist-line 4 from the hoisting drum 5 passes over and around sheaves 6 and 7 of the crane, and a motor 8 is mounted on the chassis, with transmission gearing 9, 9 for operating the hoisting drum. Customary or suitable control means (not shown) are provided for controlling the driving and transmission means between the motor and the hoisting drum, and these manual control means are arranged in position for ready access of the operator who stands upon the deck 10 of the truck.

15 The lifting and carrying mechanism of my invention includes a vertically swinging boom 10, which is made up of two forwardly converging and rigidly connected metal channel plates, and the boom is pivoted at its rear end upon a horizontal transversely extending rock-shaft 11 mounted in the plates of the uprights of the fixed crane.

20 At its free front end the boom is provided with a carrier that includes a throat or U-shaped yoke 12 that is rigidly united in suitable manner with the spaced plates or arms of the boom. The semi-circular or bowed portion of the yoke merges with two spaced parallel and straight arms of the yoke, and slots 13, 13 are provided in the yoke extending outwardly from the bow of the yoke and terminating in openings at the front free ends of the yoke.

25 The yoke forms part of the load carrier, and it supports and guides a pair of opposed, arcuate or segmental clamping jaws 14, 14, mounted within the slotted yoke and movable forwardly to closed or clamping position on the straight arms of the yoke, and movable rearwardly to retracted or open position within the bowed portion of the yoke.

30 For this purpose each clamping jaw is equipped with a centrally located outwardly radiating trunnion 15 which passes through a guide slot 13 of the yoke and is provided with anti-friction guiding and sliding collars 16 for co-action with the slotted yoke.

35 In the retracted or open position of the jaws in Fig. 1, they are retained against displacement in open housings 17, 17, fashioned from channel iron plates and rigidly attached within the bow portion of the yoke.

40 For imparting opening and closing movements to the pair of jaws, a manually operated control lever 18 is pivotally mounted at 19 on a suitable

fixed support for ready access to the operator of the hoist, and this lever is pivotally connected by a link 20 to a short rock-arm 21 rigid with the rock shaft 11 and located on a projecting end of the shaft exterior of the uprights 1.

At the longitudinal center of the rock shaft a longer rock-arm 22 is rigidly mounted, and this arm is connected by a link 23 to a sliding cross-head 24 having its opposite ends slidably mounted in longitudinal grooves 25 of the spaced arms forming the boom 10.

The sliding cross-head 24 transmits movement and power through a pair of laterally spaced and outwardly flared or diverging links 26, which are pivoted at 27, 27 to the trunnions or bosses 15 of the clamp jaws.

A well known or conventional type of cylindrical metallic drum or container D is illustrated in the drawings, as a load, and the drum is provided with the usual chime C at its upper open end.

With the clamping jaws retracted, the crane truck is run into position of Fig. 1 with the boom lowered so that the carrier is below the chime of the drum, and the yoke of the carrier in position so that the clamping jaws are ready to be moved forward to grasp or clamp the drum. The lever 18 is now pulled to the rear sufficiently to activate the linkage and project the jaws to clamping position about the drum as indicated in Fig. 3. In sliding away from the bow of the yoke projected jaws are drawn by the straight arms of the yoke nearer to and concentric with the vertical axis of the drum, and the jaws are thus rigidly clamped about the drum below its chime, and the load may be lifted through use of the hoist line 4, the drum 5, and the hoisting mechanism under manual control of the operator.

Due to the flexibility of the linkage in the lifting mechanism, the diametrically arranged trunnions provide a swiveled support for the drum D, in order that the drum may remain in level position as it is lifted or hoisted by vertical upward swing of the boom, and in position of Fig. 4 the drum may be transported to an unloading station.

For unloading, the boom and drum are lowered by the hoist-line until the drum rests upon a support, then the lever 18 is pushed forward from position of Fig. 4 to that of Fig. 2 to withdraw the clamping jaws from the drum, thereby releasing the drum from the carrier.

Having thus fully described my invention, what I claim as new and desire to secure by Letters Patent is:

1. In a portable crane of the vertically swinging type, the combination with a hoisting-boom and operating means therefor, of a carrier rigid with the boom and including a U-shaped yoke, slots in the yoke extending outwardly from the bow of the yoke and terminating in openings at the front free ends of the yoke, a pair of opposed clamping jaws, a trunnion on each opposed jaw slidably mounted in its respective slot in the yoke, and adapted to be projected forwardly in the slots into diametrical arrangement with each other to effect clamping engagement with an

article to be lifted, and manually controlled means for operating the jaws.

2. In an automotive crane truck of the vertically swinging type, the combination with a pivoted hoisting-boom and operating means therefor, of a slotted U-shaped yoke rigid with the boom, open ended slots in the yoke longitudinally thereof, a pair of clamping jaws having trunnions slidably mounted in the slots in the yoke, and lever actuated mechanism operatively connected with said trunnions for projecting and retracting the jaws with respect to the slots in the yoke to effect clamping engagement with an article to be lifted.

3. In an automotive crane truck of the vertically swinging type, the combination with a pivoted hoisting-boom and operating means therefor, and a longitudinally slotted U-shaped yoke rigid with the free end of the boom, of a pair of clamping jaws having trunnions slidably mounted in the slots in the yoke, a pair of jaw-retaining housings mounted within the bow of the yoke, and lever actuated mechanism operatively connected with said trunnions for projecting and retracting the jaws with respect to the slots in the yoke to effect clamping engagement with an article to be lifted.

4. In a lifting hoist mechanism, the combination with a support, a rock-shaft mounted therein, a boom pivotally mounted on the shaft, and hoisting means for the boom, of a U-shaped yoke rigid with the free end of the boom, open ended slots in the yoke longitudinally thereof, a pair of opposed clamping jaws having trunnions slidably mounted in the slots in the yoke, lever mechanism for rocking the shaft, and operative linkage connecting the shaft with said trunnions for projecting and retracting the jaws with respect to the slots in the yoke to effect clamping engagement with an article to be lifted.

5. In a lifting hoist mechanism, the combination with a support, a rock-shaft mounted therein, a boom pivotally mounted on the shaft and provided with longitudinal slots, and hoisting means for the boom, of a longitudinally slotted U-shaped yoke rigid with the free end of the boom, a pair of opposed clamping jaws having trunnions slidably mounted in the slots in the yoke, a slideable cross-head mounted in the slots of the boom, and links operatively connecting the cross-head with said trunnions, and lever actuated mechanism for rocking the rock-shaft including linkage between the shaft and said cross-head.
